UNITED STATES PATENT OFFICE.

WILLIAM A. HOLDINGHAUSEN, OF CLOVIS, NEW MEXICO.

ENGINE.

Application filed January 19, 1920. Serial No. 352,417.

To all whom it may concern:

Be it known that I, WILLIAM A. HOLDINGHAUSEN, a citizen of the United States, residing at Clovis, in the county of Curry 5 and State of New Mexico, have invented certain new and useful Improvements in Engines, of which the following is a specification.

This invention relates to a steam engines 10 and has for its object the provision of a novel construction by the use of which the driving shaft may be rotated in either direction and power will be applied continuously thereto. The invention seeks to provide 15 novel means for controlling the flow of steam to the shaft propelling members and exhausting the steam therefrom, and also seeks to provide a construction which will utilize the expansive force of the steam in 20 such a manner as to avoid loss of energy and effect an economy in use of fuel. Incidental objects of the invention will appear in the course of the following description.

In the accompanying drawings—

Figure 1 is an elevation of an engine embodying my improvements;

Fig. 2 is a longitudinal section of the same on the line 2—2 of Fig. 1;

Fig. 3 is a transverse section on the line 30 3—3 of Fig. 2;

Fig. 4 is a transverse section on the line 4—4 of Fig. 2;

Fig. 5 is a detail sectional elevation, the section being approximately on the line 35 5—5 of Fig. 2;

Fig. 6 is a similar view approximately on the line 6—6 of Fig. 2.

In carrying out my invention, I employ a cylindrical casing in the ends of which 40 a driving crank shaft is journaled and upon one end of which is mounted a plurality of valves for controlling the admission and exhaust of steam, the crank shaft having one end extended to carry a controlling cam 45 which acts upon the stems of said valves. In the drawings the reference numeral 1 indicates one end plate of the cylindrical casing and 2 indicates a head plate forming a part of the circumferential wall of the 50 casing. A plurality of said head plates is provided, the number being determined by the number of working chambers within the casing and between the opposed edges of adjacent head plates are fitted corner bars or strips 3 which are rigidly secured 55 to the head plates by cap bolts 4 and on their inner sides, carry partitions 5 which extend into the casing between the end plates of the same and divide the casing interiorly into an annular series of working chambers. 60 Upon reference to Fig. 4, it will be noted that the partitions 5 are arcuate, the arc defined by each partition being concentric with the pivot 6 of a blade 7 which works within the chamber defined by successive partitions. 65 The pivot 6 is located in the angle formed by the inner face of a head block 2 and the convex face of an adjacent partition and the blade 7 extends from the pivot across the working chamber to the partition at the opposite side of the chamber. The pivot 6 is a rod or long pin which extends through the end walls of the casing and has its ends fitted in socket plates 8 secured upon the outer surfaces of the end walls. The pivotal edge of 70 the blade is formed with a hinge or sleeve member 9 through which the said pivot rod or pin 6 passes and which seats in the adjacent partition 5, as shown at 10, said partition being constructed with a recess or cavity 75 11 within which is a packing strip 12 and a spring 13 to hold the packing against the sleeve or hinge member 10 whereby leakage of steam around or through the joint will be prevented. The free side edge and 80 both end edges of the blade are beveled, as shown at 14, and a packing strip 15 is seated on the said beveled edge so as to bear against the adjacent partition and the end walls of the chamber and prevent leakage of steam 85 90 so that the full force of the steam will be exerted upon the working face of the blade. The packing strip is held to the edge of the blade by lugs or holding strips 16 formed on or carried by the blade, as clearly shown. 95 A steam passage 17 extends from one end edge of each head plate or block 2 to a port 18, at the center of said block, which opens into the working chamber so that the steam will be directed against the working face 100 of the blade. Each blade is provided on its inner face near its free edge with a socket or lugs 19 which receive and are pivotally connected to the outer end of a connecting rod 20, the inner end of each rod being fitted 105 to the crank 21 of the driving shaft 22. In the present application I have illustrated an engine having six working chambers and, therefore, have shown six blades and six connecting rods. It will be noted that the 110 connecting rods are arranged in pairs, one rod of each pair having a box or a head 23

at its inner end which is journaled directly upon the crank 21 of the driving shaft while the other rod of the pair is shorter and has its inner end pivotally connected to a lug 24 on the box or head 23 at that side of the head opposite the side from which the longer connecting rod extends. By this arrangement, I am enabled to bring the connecting rods into a more compact space than would be possible if each rod were separately mounted upon the crank shaft and avoid the offsetting of some of the rods so that the stroke of the blade is transmitted more directly to the shaft. It will be noted 10 that the shorter connecting rod is constructed with a fork 25 at its inner end to embrace the lug 24 and a pivot pin or bolt 26 is inserted through the said fork and said lug. The ends of the crank are somewhat 15 elongated, as shown at 27, so as to furnish a counterbalance for the cranked portion of the shaft and I preferably provide anti-friction bearings, indicated at 28, in the end walls of the casing so that the frictional 20 resistance to the rotation of the shaft will be minimized.

On the end wall 29 of the casing, I form or secure a plurality of cylinders 30 which are disposed concentrically with and radially 30 to the driving shaft and have their respective ends closed by caps 31 and 32. Each cylinder is provided with a lining or bushing 33 and in each cylinder is a balanced piston valve 34. The outer cap 31 of each cylinder 35 is constructed centrally with a seat 35 to receive a spring 36 which bears upon the outer end of the valve 34 and the inner cap 32 is constructed with a gland or packing box 37 to guide the valve stem 38 and prevent leakage of steam around the same. The stem 38 is fixed to the valve 34 and bears against the controlling cam 39 which is secured upon the driving shaft by a key 40 so that while the cam may be shifted longitudinally of the shaft it is constrained to rotate therewith. A stop collar 41 is secured upon the driving shaft at the outer end of the key 40 and prevents the controlling cam being thrown beyond the key so that it cannot be moved to such a point that the valve stems will not bear upon it. The cam is constructed with an annular groove 42 adjacent its outer end in which groove is engaged the end of a shifting lever 43 which may be fulcrumed in 55 any convenient manner adjacent the engine and equipped with any desired means for holding it in a set position. The cam is constructed with two circumferential working faces 44 and 45 which are duplicates in 60 form but are arranged reversely one to the other so that the driving shaft will be caused to rotate in one or the other direction accordingly as one or the other working face is brought to bear upon the inner ends of the 65 valve stems. The working faces are separated

by a circular concentric circumferential face 46 and when the cam is shifted so that the said face 46 is engaged by the inner ends of the valve stems all the valves will be brought to their innermost positions and, consequently, the engine will remain neutral and inoperative inasmuch as no steam will be permitted to pass by the valves but all the steam will be held quiescent in the groove 70 48. It will be readily noted that the several springs 36 act in opposition to the cam 44 or 45 so as to hold the valve stems in engagement with the working cam and thereby insure the proper operation of the valves. 75 Each valve has a minute passage 47 extending longitudinally therethrough so that any steam which may possibly leak past the packing strips at the inner end of the valve will be permitted to flow to and through the outer end of the valve and thence escape 80 through the exhaust port so that it will not be trapped at the inner end of the valve cylinder to create back pressure upon the valve which would interfere with its proper 85 operation. In the end wall 29 of the engine 90 casing, adjacent each cylinder 30 are three ports 48, 49 and 50, the intermediate port 49 forming the outer end of the passage 17 in the adjacent head block 2 and the ports 48 and 50 forming branches from the annular grooves 51 and 52, respectively, in the 95 wall 29. All the ports open into annular grooves in the wall of the valve cylinder and ports are formed in the bushing 33 to 100 permit flow from the respective grooves. The central groove 53 and the ports 54 are merely a transfer channel, the live steam flowing therethrough from the cylinder to the working chamber to actuate the blade or piston and the exhaust steam flowing in 105 the opposite direction from the working chamber to the cylinder through the same ports. The groove 51 is a steam supply 110 groove, live steam being fed to said groove through an inlet 55, provided at any convenient point in the casing, and passing to the valve cylinder through the groove 56 and ports 57, while the groove 52 is an exhaust or escape flue, being provided with an outlet 58 at any convenient point and receiving the exhaust steam through the groove 59 and ports 60. The valves 34 are of the balanced piston type and each consists of an intermediate reduced body portion and a head 61 at each end of the body 115 portion provided with packing which fits closely to the bushing or lining 33 so that the flow of steam past the ends of the valve will be prevented and the steam directed into the working chambers or permitted to exhaust 120 therefrom according to the position of the valve. Referring to Fig. 2, when the valve is in the position shown at the top of the figure, the steam admitted to the inlet passage 48 will flow through the adjacent 125 130

groove 56 and ports 57 into the chamber defined by the bushing 33 and the valve and will then flow from said chamber into the port 49 and thence through the passage 17 and port 18 into the adjacent working chamber. When the valve is in the position shown at the bottom of Fig. 2, the passage 17 will be in communication with the exhaust port 50 and cut-off from the inlet passage 48 so that steam entering the valve cylinder from the inlet passage will be held in the chamber defined by the bushing or lining and the valve, and the steam in the adjacent working chamber may escape therefrom and enter the exhaust passage so as to flow into the open air or be carried back to a condenser or the boiler.

The positions of the valves in Fig. 3 correspond to the positions of the blades in Fig. 4. Referring to said figures, it will be noted that the valve *a* is in such a position that the ports 60 are closed and the inlet ports 57 are in communication with the ports 54 and steam will flow to the adjacent working chamber, the working blade in said chamber being at the outer limit of its movement. The valve *b* is at the outer limit of its movement, like the valve *a*, and the port leading to the adjacent working chamber is fully uncovered so that the full force of the steam is admitted to the said chamber and the blade therein receives the full pressure of the steam, but said blade has been moved partly inward. The valve *c* is in such position that the port leading to the adjacent working chamber is fully covered and, consequently, the blade in the corresponding working chamber is being forced inwardly by the expansion of the steam in said chamber unaided by the impact or velocity of the steam, the live steam merely flowing around and past the valve. The next valve *d* is in exhaust position under the combined action of the cam and the spring 36 so that while the blade in the adjacent working chamber is at the inner limit of its stroke the steam is beginning to exhaust from said chamber through the ports 54 and 60 so that the blade may move outwardly. The valves *e* and *f* are also in exhaust position and the blades of the corresponding working chambers are moved partly outward through the rotation of the crank shaft. By referring to Fig. 4, it will be noted that while the connecting rod of the blade corresponding to the position *a* is apparently on a dead center, the connecting rod of the blade in the position *b* is exerting pressure across the crank shaft so that the shaft will be rotated to the left and the pressure of the blade in the position *a* will be exerted upon the shaft to continue the rotation as soon as the dead center is cleared. While the pressure upon the blade in the position *a* may possibly be greater than in the other

position named the expansion of the steam in the position *c* is applied in conjunction with the pressure from the position *b* so that the dead center will be readily passed and the crank shaft rotated positively and continuously. If it be desired to rotate the crank shaft from left to right of Fig. 4, the controlling lever 43 is swung so as to shift the cam outwardly and bring the working surface 45 into engagement with the inner ends of the several valve stems so that the initial pressure will be exerted at the left side of the engine instead of the right side as in the position shown, the engine being illustrated as arranged to rotate from right to left.

It will be noted that the valve controlling cam has its working face formed in three sections, each of which is concentric with the driving shaft and is connected with the meeting sections by shoulders or drops. The highest elevation or that portion 62 of the cam having the greatest radius is the feeding portion and holds the valve in the position *a* of Fig. 3 as long as it bears upon the valve stem. As the shaft 22 rotates, the cam will be likewise rotated and the intermediate or lap portion 63 of the cam will be brought into engagement with the valve stem and the valve shifted so that the live steam will be cut off and the blade will then be actuated solely by the expansion of the steam. The continued rotation of the cam will bring the lowest portion 64 of its working surface into engagement with the valve stem whereupon the exhaust port will be opened to the working chamber and the steam will be discharged. It is to be noted that the exhaust surface 64 is long enough to engage three valve stems at one time and the exhaust is consequently open long enough to discharge all the spent steam. Under some conditions, it may be possible and desirable to shorten the period of steam admission and, to accomplish this result, I dispose the shoulder or drop between the portions 62 and 63 obliquely, as shown at 65 in Fig. 2, thereby giving the feeding portion 62 a variable circumferential extent so that by shifting the cam longitudinally of the shaft, the point at which the steam will be cut off may be varied.

My engine is simple in the construction and arrangement of its parts, is compact and may be very easily manufactured, assembled or repaired. The power of the steam is utilized fully so that the crank shaft will be rotated continuously and it obviously may be extended to any desired point and connected with machinery to be driven through any convenient form of gearing. The engine is well balanced so that it will run evenly and smoothly and power will be applied uninterruptedly to the crank shaft, there always being three

working chambers receiving steam and three exhausting.

Having thus described the invention, what is claimed as new is:

5 1. An engine having an approximately cylindrical, stationary casing, said casing, comprising a plurality of head plates, corner bars inserted between said head plates and securely attached thereto by means of bolts 10 or the like, arcuate partitions on said corner bars extending inwardly in substantially radial direction between said head plates to form abutments, said partitions being arcuate, a working chamber being formed between each pair of adjacent partitions and an intermediary head plate; a flat blade in each of the said working chambers hinged on the partition in the corner formed between the head plate and the convex side of 20 one of the said partitions, said flat blade extending across the chamber and adapted to contact with the convex side of the other partition forming said chamber, the convex side of each partition being concentric with the axis of the hinge in its chamber; a crank shaft extending axially through the casing, linked connection between said crank shaft and each of said blades, means for admitting fluid under pressure to, and exhausting it from the several chambers successively, packing strips along the working edges of each blade, and holding fingers for securing said strips to each blade.

15 2. An engine having an approximately cylindrical, stationary casing, said casing comprising a plurality of head plates, corner bars inserted between said head plates and securely attached thereto by means of bolts 25 or the like, arcuate partitions on said corner bars extending inwardly in substantially radial direction between said head plates to form abutments, said partitions being arcuate, a working chamber being formed between each pair of adjacent partitions and an intermediary head plate; a flat blade in each of the said working chambers hinged on the partition in the corner formed between the head plate and the convex side of one of 30 the said partitions, said flat blade extending across the chamber and adapted to contact with the convex side of the other partition forming said chamber, the convex side of each partition being concentric with the axis of the hinge in its chamber; a crank shaft extending axially through the casing, linked connection between said crank shaft and each of said blades, and means for admitting fluid under pressure to, and exhausting it from the several working chambers successively.

35 3. An engine having an approximately cylindrical, stationary casing, said casing comprising a plurality of head plates, corner bars inserted between said head plates and securely attached thereto by means of bolts 40 or the like, arcuate partitions on said corner bars extending inwardly in substantially radial direction between said head plates to form abutments, said partitions being arcuate, a working chamber being formed between each pair of adjacent partitions and an intermediary head plate; a flat blade in

each of said working chambers hinged on the partition in the corner formed between the head plate and the convex side of one of said partitions, said flat blade extending across the chamber and adapted to contact with the convex side of the other partition forming said chamber, the convex side of each partition being concentric with the axis of the hinge in its chamber; a crank shaft extending axially through the casing, linked connection between said crank shaft and each of said blades, means for admitting fluid under pressure to, and exhausting it from the several chambers successively, packing strips along the working edges of each blade, and holding fingers for securing said strips to each blade.

45 3. An engine having an approximately cylindrical stationary casing, said casing comprising a plurality of head plates, corner bars inserted between said head plates and securely attached thereto by means of bolts 50 or the like, arcuate partitions on said corner bars extending inwardly in substantially radial direction between said head plates to form abutments, said partitions being arcuate, a working chamber being formed between each pair of adjacent partitions and an intermediary head plate; a flat blade in each of the said working chambers hinged on the partition in the corner formed between the head plate and the convex side of one of the said partitions, said flat blade extending across the chamber and adapted to contact with the convex side of the other partition forming said chamber, the convex side of each partition being concentric with the axis of the hinge in its chamber; a crank shaft extending axially through the casing, linked connection between said crank shaft and each of said blades, and means for admitting fluid under pressure to, and exhausting it from the several working chambers successively.

In testimony whereof I affix my signature.
WILLIAM A. HOLDINGHAUSEN. [L. S.]
